P. HALPERIN

GARMENT

Filed Aug. 1, 1925

INVENTOR.
PHILLIP HALPERIN

BY *Fred D. Hayn*
ATTORNEY.

UNITED STATES PATENT OFFICE.

PHILLIP HALPERIN, OF LOS ANGELES, CALIFORNIA.

GARMENT.

Application filed August 1, 1925. Serial No. 47,510.

My invention relates to garments for both old and young, and of both sexes, and more particularly to those garments especially adapted for children of tender age whereby 5 said children may be able to fasten and unfasten the garment without the aid of a grown person.

It accordingly is an object of my invention to provide a garment with a rear part 10 having but one portion thereof associated with the back of said garment, said rear part being adapted to be raised or lowered in relation to said garment, said rear part being provided with a set of fasteners 15 adapted to coact with complementary fasteners on the front of the garment so that said rear part may be detachably secured to said garment, and when so secured may hold said rear part in position irrespective of the 20 position of the wearer.

Another object of my invention is to provide a novel form of garment in which a rear part has a channel associated therewith, said channel having positioned there- 25 in and stitched thereto at substantially the middle portion thereof, a belt formed of part elastic and inelastic portions, said stitches being coarse, so that when the elastic portion has become worn, said belt may 30 be easily and expeditiously renewed.

If desired, it is also within the province 35 of my invention to equip my garment with a pair of pockets, at the front and side of said garment, each of which pockets may be provided with a reinforcing tab so that 40 a fastener may be secured to each in order that said fasteners may not easily be torn therefrom, due to rough usage, or said pockets and tabs may be omitted, other reinforcing means being substituted therefor.

A further object of my invention is to provide a simple and inexpensive means whereby an artistic and attractive, yet withal a serviceable garment may be produced, which 45 garment may be expeditiously put on or removed by the wearer.

Further objects and advantages of my invention will become more apparent as the description thereof proceeds.

Reference is had to the accompanying drawings, in which similar reference characters denote similar parts. In the drawings,

Fig. 1 is a front elevational view of a 55 garment provided with my invention, one

of the tabs of the belt being shown unfastened,

Fig. 2 is a rear elevational view of the garment with the rear part fastened in position on the front of the garment, 60

Fig. 3 is a side elevational view of the garment applied to a wearer, showing the rear part lowered,

Fig. 4 is a fragmentary rear elevational view showing the rear part of the garment 65 in lowered position, and

Fig. 5 is a detail plan view of the inner belt removed from the garment.

Describing my invention more in detail, as is well-known, children of tender age invariably require mature aid when dressing or undressing, or in attending to their daily needs. I have therefore produced a novel form of garment in which such children are able to take care of themselves without any 70 such aid whatever.

While on the drawings I have shown my garment as fashioned as a "coverall," and as particularly applicable as a garment for children, I desire it to be distinctly understood that my invention is not to be limited thereto, and that it may equally well be applied to garments used by grown persons. My invention may be applied to pajamas, 75 coveralls, overalls, and the like, used by both 80 children and grown persons.

As shown in the drawings, the garment comprises an upper portion 1, which has preferably, though not necessarily, a lower portion 2 integral therewith, said lower portion being provided with a rear part 12 entirely free from the upper portion 1, as more particularly shown in Figs. 3 and 4, 85 said rear part having stitched to its upper portion a channel 3 adapted to have positioned therein and stitched thereto by coarse stitches 11 at substantially the middle portion thereof a belt 4. The coarse stitches 11 are provided so that said belt 4 may be quickly and easily removed from said channel for reasons that will presently appear. 90 Of course, it will be obvious that if desired the belt may be permanently secured to the channel and still be within the province of my invention.

As seen more particularly in Figs. 1 and 2, the garment may have stitched thereto a pair of pockets 10, preferably positioned as shown, which pockets may be equipped with tabs 9, either integral therewith or se- 100 105 110

ured thereto in any preferred manner. I use these tabs as a reinforcing means for holding in place a button or other fastener 8, though the pockets and tabs may be omitted and other reinforcing means provided. Said pockets and tabs however form an embellishment for the garment.

The belt 4 preferably comprises an elastic or resilient portion 7, to each end of which is secured as by sewing or other means an inelastic tab 5 equipped with a fastener 6 complementary to the fastener 8, in the present instance being an ordinary button hole. It will be clear that other fasteners may be substituted for those shown and described.

The belt 4 is slipped through the channel 3 and stitched in place by means of the coarse stitches 11, as above explained. This feature of my invention prevents the belt 4 from inadvertently being removed or pulled out of the channel 3. Moreover, the stitches 11 permit the ready removal of the belt 4 so that the elastic portion 7 may be renewed when worn. It will also be understood that other means than the stitches 11 may be used instead, for detachably holding the belt 4 in place, and still remain within the province of my invention.

Attention is directed to the fact that the elastic belt 4 holds the rear part 12 in place, irrespective of the position the wearer may take. Said rear part being unconnected with the upper portion 1, a considerable play between the parts is permitted, avoiding entirely the snapping off of buttons or other fasteners commonly associated with this form of garment, and also provides properly for the growing of the child wearing said garment, since there is ample material underneath said rear part to accommodate such growth.

In use, the rear part 12 is pulled up in position by means of the tabs 5, which may be easily reached, and said tabs are buttoned in place on the front of the garment. The unbuttoning of the garment is accomplished as easily as the buttoning, and the rear part 12 may be quickly lowered, and all may be done by children of a very tender age, this being a boon to the mothers of said children.

While I have thus described my invention with great particularity, it will be obvious that the same may be modified throughout a

wide range. I therefore do not propose to be limited to the exact details of construction shown and described, but reserve the right in practice to make any and all modifications thereof that fall within the scope of the appended claims.

I claim as my invention:

1. In a garment, in combination, a rear part, a channel stitched to said rear part, a removable part-elastic belt positioned in and stitched to said channel by means of coarse stitches, and a set of complementary fasteners on the end portions of said belt and on the front portion of said garment, whereby said rear part may be secured to said garment at the front or unfastened and lowered over the rear of said garment.

2. In a garment, in combination, an upper portion, a lower portion associated with said upper portion, a rear part associated with said lower portion, a free and unobstructed channel stitched to said rear part, a removable part-elastic and part-inelastic belt detachably associated with said channel, means for temporarily securing said belt in said channel so that it may not be accidentally removed from said channel, and means associated with each end of said belt and on each side of the front portion of said garment whereby said rear part may be detachably fastened on the front of said garment so that said rear part will be held in position without binding.

3. In a one-piece garment, in combination, a rear part adapted to be raised and overlap the upper part of said garment, or lowered over the lower portion of said garment, a channel stitched to the top of said rear part, a removable belt in said channel, said belt being provided with an elastic portion in the middle part thereof, means associated with said belt and said channel for temporarily anchoring said belt in position in said channel, said belt extending only a short distance beyond the sides of said garment, and a set of complementary fasteners on each end of said belt and on said garment, said belt, when secured to said garment preventing said rear part from sagging.

In testimony whereof I have signed my name to this specification.

PHILIP HALPERIN.
